UNITED STATES PATENT OFFICE.

EDWARD W. CARNES, OF CHICAGO, ILLINOIS, ASSIGNOR TO AMERICAN CAN COMPANY, OF NEW YORK, N. Y., A CORPORATION OF NEW JERSEY.

SHEET-METAL BOX.

1,072,820.

Specification of Letters Patent.

Patented Sept. 9, 1913.

Application filed March 26, 1910. Serial No. 551,623.

To all whom it may concern:

Be it known that I, EDWARD W. CARNES, a citizen of the United States, residing in Chicago, in the county of Cook and State of

5 Illinois, have invented a new and useful Improvement in Sheet-Metal Boxes, of which the following is a specification.

My invention relates to the construction of rectangular sheet metal boxes of the kind 10 wherein the sides and ends of the body are integral with the bottom, the blank from which the box body and bottom are integrally formed being notched or cut away at the corners, and in which the flange of 15 the cover is formed by a right angle fold, and also notched at the corners.

In the improved construction embodying my invention, the upright meeting edges of the integral sides and ends of the box body 20 are united by an internal lock seam, flush with the outer face of the upright ends of the body, and the body is furnished with slightly rounded corners, and the flange of the cover is notched for only a portion of its 25 depth, preferably about half its depth, and the flange of the cover is a combined drawn and folded flange, the corners of the cover being slightly rounded to enable the cover flange to be drawn at the corners without 30 breaking or injuring the stock, and the rounded formation of the box body at the corners effecting a snug, tight fit with the rounded corner cover. The partially drawn construction of the cover flange at the corners adds materially to the strength and 35 durability of the cover and the perfection of the closure effected thereby, and also produces a much smoother, neater and better appearing box.

40 My invention also consists in the novel construction of parts and devices and in the novel combinations of parts and devices herein shown and described, and more particularly specified in the claims.

45 In the accompanying drawing forming a part of this specification, Figure 1 is a perspective view of a sheet metal box embodying my invention. Fig. 2 is a plan view of the same with the cover removed. Fig. 3 is 50 a detail bottom plan view of the cover. Fig. 4 is an enlarged horizontal cross section through one corner of the box body. Fig. 5 is an enlarged horizontal section through one corner of the cover on line 5—5 of Fig. 55 1. Fig. 6 is a detail plan view showing the

blank from which the box body and bottom are formed, and Fig. 7 is a detail view of the blank from which the cover is formed. Figs. 8 to 16 show modifications.

In the drawing, A represents the box 60 body, the same having an integral bottom a, integral upright sides a¹ and integral upright ends a², the meeting edges of the sides and ends being united at the corners by internal lock seams a³ which are formed 65 flush with the outer face of the upright ends a². At the corners, the box body is furnished with slightly rounded corner walls a⁴ to adapt the same to form a snug, tight fit with the drawn and rounded portion of 70 the cover flange at the corners of the cover. The blank A¹ from which the box body is formed has cut away portions A² at the corners to enable the upright sides and ends to be folded or turned at right angles to the 75 box bottom.

The sheet metal cover B is provided with a marginal depending combined drawn and folded flange b, the drawn portion of the flange b¹ at the corners being rounded and 80 extending to about half the depth of the flange and the intermediate portion of the cover flange between the corners being formed by turning or folding the same at right angles to the face or plane of the 85 cover. The cover flange at the corners is furnished with curved notches b² which extend preferably slightly more than half the depth of the flange, thus partially separating the side portion b³ from the end portion 90 b⁴ of the cover flange. The rounded, drawn corner portion b¹ of the cover flange integrally unites the end portions and side portions of the cover flange at the corners and thus securely binds the side portions and 95 end portions together, and effectually prevents any tendency of either the side or end portions of the cover flange from spreading or flaring outward as is the case where the cover flange is notched at the corners to its 100 entire depth.

My improved construction of folded box body and cover not only adds materially to the strength and durability of the box but also produces a much better and neater article in all respects than the constructions heretofore in use.

In the modification or further improved construction of my box shown in Figs. 8, 9 and 10, (Fig. 8 being a perspective view, 110

Fig. 9 a rear elevation and Fig. 10 a cross section on line 10—10 of Fig. 9,) the construction is the same as above described and shown in Figs. 1 to 7, with certain further features added, the cover being hinged and provided with a catch to hold it closed, and the body being provided with horizontal convex or outwardly projecting beads a^5 at its sides and ends terminating a little short of the corners, so that the beads will not interfere with the lock seaming of the sides and ends together at the corners. The convexly curved beads a^5 serve to stiffen the sides and ends of the box body and also as stops for the flange of the cover to shut down against. As shown in Figs. 8 to 10, the back side of the body is furnished with a concave or inwardly projecting bead a^6 at its central or middle portion, separated by slits a^7 from the two terminal convex portions a^8 of the bead to receive the pin or pintle C of the hinge, and form an eye to hold it in position on the box body. The hinged pintle C is prevented from slipping endwise by the shoulder a^9 formed by the outer ends of the convex portions a^8 of the bead. The concave central portion a^6 of the bead on the back side of the body is enlarged at its middle part a^{10} to receive and accommodate the hinge eye b^5 on the back portion b^4 of the flange of the cover, this hinge eye being formed by providing said back flange of the cover with an integral projecting tab and curling it into a roll or cylindrical form to embrace the central portion of the hinge pintle C. The interengaging catches b^3 and b^6 on the box body and cover for holding the cover closed are preferably integral horizontal lugs or short beads stamped in the front side of the box body near the middle and upper edge thereof and in the front portion of the cover flange. To further stiffen the cover and the box as a whole and improve its appearance, the cover as shown in Figs. 8 to 10 is provided with an upwardly or outwardly projecting panel b^7 .

In the modification illustrated in Fig. 11, which is a cross sectional view, the construction is the same as in Figs. 8 to 10 above described, excepting that the body of the box is provided with a necked in upper portion a^{12} forming a horizontal shoulder a^{13} for the cover to shut down against.

In the modification illustrated in Figs. 12 to 13, (the former being a rear elevation, and the latter a cross section on lines 13—13 of Fig. 12,) the construction is similar to that before described, excepting that the hinge eye on the body of the box instead of being formed integral with the back side of

the box is made of a pair of separate piece tabs b^8 , each having an eye portion b^9 embracing the pintle of the hinge and end portions b^{10} inserted through slots b^{11} in the back side of the box body and turned in opposite directions flat against the inside face of the back side of the box.

In the modification illustrated in Fig. 14, which is a cross sectional view, the cover instead of having an upwardly projecting panel b^7 has a downwardly or inwardly projecting panel b^{12} , and the upright sides and ends of the box body are provided with integral internal folds a^{14} at their upper edges to stiffen the sides and ends of the box and give it a smooth edged mouth.

In the modification illustrated in Figs. 15 and 16, the former of which is a cross sectional view, and the latter of which is a detail view of one of the separate piece hinge tabs in the flat, the construction is the same as shown in Figs. 12 and 13, excepting that the separate piece hinge tab for connecting the hinged pintle with the box body is furnished with two tongues or lips, the box body being provided with two slots for each hinge tab through which said tongues are inserted and bent in opposite directions.

I claim:

1. A sheet metal box comprising a body portion and a cover having a flange, said body portion being provided with horizontal beads for the flange of the cover to shut down against, said cover flange comprising combined, folded and drawn portions and being notched at the corners, the drawn portions of the cover being above the notched portions.

2. A box cover having a combined folded and drawn flange notched at the corners to a portion of its depth, substantially as specified.

3. A box cover having a flange notched to a portion of its depth at the corners, and provided with an integral drawn portion above the notches at the corners of the cover, substantially as specified.

4. A box cover having a flange notched to a portion of its depth at the corners, and provided with an integral drawn portion above the notches at the corners of the cover, said drawn corner portions of the cover flange being rounded, and the portions between the corner portions being flat, substantially as specified.

EDWARD W. CARNES.
